UNITED STATES PATENT OFFICE.

FREDERICK W. KOONZ, OF MELROSE, MASSACHUSETTS, ASSIGNOR TO SHEPARD MANUFACTURING COMPANY, OF MELROSE, MASSACHUSETTS, A CORPORATION OF CONNECTICUT.

DESIGN FOR A BROOCH.

41,186.

Specification for Design.

Patented Feb. 21, 1911.

Application filed December 17, 1910. Serial No. 597,951. Term of patent 3½ years.

To all whom it may concern:

Be it known that I, FREDERICK W. KOONZ, a citizen of the United States, residing at Melrose, in the county of Middlesex, State of Massachusetts, have invented a new and original and ornamental Design for Brooches, of which the following is a specification, reference being had to the accompanying drawing, forming part thereof.

The figure is a plan view of a brooch, showing my new design.

I claim:

The ornamental design for a brooch, as shown.

FREDERICK W. KOONZ.
